UNITED STATES PATENT OFFICE

ADOLPH G. LOTTER, OF MILWAUKEE, WISCONSIN, ASSIGNOR TO STATIONERS LOOSE LEAF CO., OF MILWAUKEE, WISCONSIN, A CORPORATION OF WISCONSIN

LOOSE-LEAF BINDER

Application filed February 8, 1929. Serial No. 338,451.

This invention relates to certain new and useful improvements in loose leaf binders and refers more particularly to visible record binders such as illustrated in Letters 5 Patent No. 1,727,348, issued September 10, 1929.

In binders of this type the sheets are retained by two series of separable impaling prongs, which when engaged form rings and 10 when separated are movable longitudinally to a staggered position to facilitate the insertion of additional leaves in proper staggered position.

As binders of this type are essentially ring 15 binders, they have been encumbered with the inherent objection to this type of binder viz, the tendency for the leaves to bind on the rings as the covers are closed. This objection has been overcome to a great extent by 20 the provision of followers movable with the covers to guide the leaves, but due to the particular construction of visible record binders, maximum efficiency can not be obtained from the followers, and therefore, this invention 25 has as one of its objects to increase the effectiveness of the followers in binders of the character described to facilitate the closing of the binder and to prevent tearing of the leaves at their openings through which the 30 impaling prongs pass.

Another object of this invention resides in the provision of means for increasing the ease of operation of binders of the character described, which is extremely simple and may 35 be applied to binders at the time of their manufacture or to those already in use.

The followers, as in all ring binders, have openings through which the impaling prongs pass and are also connected with the cover 40 members and as at least one series of impaling prongs is longitudinally shiftable this invention has as a further object the provision of novel means for connecting the follower member which cooperates with said series of 45 prongs, with its respective cover, which accommodates the movement of the follower with the impaling prongs upon longitudinal shifting thereof and which greatly simplifies the assembly of the binder.

50 With the above and other objects which

will appear as the description proceeds, my invention resides in the novel construction, combination and arrangement of parts substantially as hereinafter described and more particularly defined by the appended claims, 55 it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

50 Figure 1 is a plan view with parts broken away, illustrating a binder constructed in accordance with my invention and showing the inside of the back, the covers being in open position;

55 Figure 2 is a view similar to Figure 1 with the impaling prongs in staggered relation;

60 Figure 3 is an end view showing the covers partially closed to illustrate the novel means employed to prevent binding, and

65 Figure 4 is an enlarged perspective view of one end of one of the followers.

70 Referring now more particularly to the accompanying drawings, in which like numerals designate like parts throughout the several views, the numeral 5 represents the back of a visible record binder which is tubular in construction to receive the mechanism, such as shown in my patent above referred to, for mounting a plurality of spaced 75 retainer rings 6 consisting of two series of impaling prongs 7 and 8. The prongs 7 and 8 are separable to permit the insertion and removal of record leaves 9, shown in dotted lines in Figure 3, by means of said mechanism, 80 upon separating lugs 10 and 11.

85 The impaling prongs 8, in addition to being movable in a transverse plane upon the separation of the lugs 10 and 11, are shiftable longitudinally to a staggered position illustrated in Figure 2, this being accomplished by moving the lug 11 inwardly after it has been moved to its outermost position, and moving both lugs toward each other. The 90 operation of the mechanism whereby these 95

movements of the impaling prongs are obtained, forms no part of this invention and is therefore not herein shown nor described.

Heretofore, in conventional ring binders, the cover members have been pivoted directly to the back. This construction had numerous objections which are overcome by connecting each of the covers 12 and 13 with the back 5 through intermediate hingedly connected members 14 and 15, the members 14 being hingedly connected with the opposite sides of the back 5 and the free ends of the members 15 being hingedly connected with the covers 12 and 13, as at 16. This construction is substantially as shown and described in Letters Patent No. 1,724,407, issued August 13, 1929.

Movable with each of the covers 12 and 13 and extended inwardly beyond the pivotal connections 16 are followers of plate form 17 and 18 respectively; the follower 17 being rigidly connected with its cover 12 and the follower 18 being movably connected with the cover 13 in a manner to be later described. The inner ends of the followers 17 and 18 are provided with a plurality of elongated apertures 19 through which the impaling prongs pass to maintain the covers properly assembled with the back.

The effectiveness of the followers to prevent binding depends roughly upon the distance between their inner edge and the inner ends of their elongated apertures 19 and as visible record binders are so constructed that when in open position there is very little room for the inner ends of the followers, their efficiency is greatly reduced.

This invention, however, overcomes this objection by means of semi-circular strips 20 which are riveted or otherwise secured to the inner edge of each follower at its under side, to ride on the inner periphery of the rings as the binder is closed. The provision of the strips 20 raises the inner ends of the followers during the initial closing movement and thus greatly increases the ease of operation and prevents binding of the leaves between the followers and the outer peripheries of the impaling prongs.

As has been stated, the follower 17 is rigidly connected with the cover 12 and the follower 18 is movably connected with the cover 13 to permit the longitudinal shifting of the follower 18 with the impaling prongs 8. The means for connecting the follower 18 with the cover 13 incorporates a plurality of key-hole slots 21 formed in the follower and through which studs 22 having enlarged heads 23 extend. In assembling, the follower 18 is connected with its cover 13 by passing the heads of the studs 22 through the large openings 24 of the key hole slots, and then shifting the same longitudinally to align the studs with the restricted portions 25 of the slots. Re-

alignment of the enlargements 24 with the heads of the studs is prevented after the follower 18 is engaged with the impaling prongs 8, as the width of the slots 19, through which the prongs pass, is not sufficient to permit the required longitudinal movement of the follower.

From the foregoing description taken in connection with the accompanying drawings, it will be readily apparent to those skilled in the art to which an invention of the character described appertains, that I provide an improved construction for visible record loose leaf binders in which followers, provided with means for preventing binding of the leaves during closing of the binder, are connected with their respective cover members in a manner which greatly facilitates assembling and which accommodates the longitudinal shifting of the impaling prongs in an extremely simple manner.

What I claim as my invention is:

1. In a loose leaf binder having a back, cover members, retaining rings carried by the back, followers carried by the cover members and engaged with the rings, and a strip secured to the inner edge of each follower and adapted to ride on the inner periphery of said rings as the covers are closed upon each other to facilitate the closing of the covers.
2. In a loose leaf binder of the character described, including a back, cover members and two series of impaling prongs carried by the back one of which is longitudinally shiftable to stagger its prongs with respect to those of the other series, followers engaged with the impaling prongs, and means connecting the follower which cooperates with the longitudinally shiftable impaling prongs with its respective cover member to accommodate longitudinal shifting thereof with its impaling prongs.
3. In a loose leaf binder of the character described including a back, cover members and two series of impaling prongs carried by the back one of which is longitudinally shiftable to stagger its prongs with respect to those of the other series, followers engaged with the impaling prongs, and means readily detachably connecting the follower which cooperates with the longitudinally shiftable impaling prongs with its respective cover member to accommodate longitudinal shifting thereof with its impaling prongs.
4. In a loose leaf binder of the character described including a back having sets of separable impaling prongs which form continuous rings, one of said sets of impaling prongs being longitudinally shiftable to a position staggered with respect to the impaling prongs of the other set, and covers, followers engaged with said impaling prongs, the follower for said shiftable prongs having longitudinal key-hole slots, and means for securing the followers to the respective covers, said

means for one cover consisting of members engageable in the key-hole slots to permit longitudinal shifting of the follower with its impaling prongs.

In testimony whereof I have hereunto affixed my signature.

ADOLPH G. LOTTER.
